Primary Examiner — Mickey Yu
Assistant Examiner — Niki Elishway(74) *Attorney, Agent, or Firm* — Greenblum & Bernstein, P.L.C.(57) **ABSTRACT**

The invention relates to a package suitable for containing a perishable product, comprising a first shell element provided with an upright circumferential edge and a central portion for accommodating said perishable product, as well as a closure element provided with a circumferential edge which closure element is placed with its circumferential edge on the upright circumferential edge of said first shell element in an adhering and closing manner and wherein said closure element is provided at its circumferential edge with a protruding lip, which lip does not adhere to the circumferential edge of said first shell element, for the purpose of peeling off said closure element from said first element. Near said lip the two circumferential edges are provided with a closed channel being in communication with said central portion, and wherein at least one of said circumferential edges is provided with a fracture line extending substantially perpendicularly to said channel.

FIG. 1a

FIG. 1b

FIG. 2a

1
PACKAGE

This application claims the benefit under 37 C.F.R. §1.53 (b) of the filing date of U.S. patent application Ser. No. 12/729,840, filed Mar. 23, 2010, which is a continuation of U.S. patent application Ser. No. 10/542,330, filed May 12, 2006, which is the U.S. National Phase of PCT/NL2004/000008, filed Jan. 8, 2004, which claims priority to Netherlands Application No. 1022368, filed Jan. 13, 2003. The entire contents of each of which is hereby incorporated herein by reference.

The invention relates to a package suitable for containing a perishable product, comprising a first shell element provided with an upright circumferential edge and a central portion for accommodating said perishable product, as well as a closure element provided with a circumferential edge, which closure element is placed with its circumferential edge on the upright circumferential edge of said first shell element in an adhering and closing manner and wherein said closure element is provided at its circumferential edge with a protruding lip, which lip does not adhere to the circumferential edge of said first shell element, for the purpose of peeling off said closure element from said first element.

Such a package is generally known, it is used for packaging products or substances, more in particular for perishable products or substances, such as foodstuffs. More specifically, such packages are used for packaging perishable foodstuffs in the form of a liquid or a gel-like substance, such as milk or yoghurt products, sweet products such as honey, jam, peanut butter, chocolate spread etc etc. Such packages are gaining in popularity these days, and consequently they are increasingly used as one-person packages.

One drawback of the one-person package that is currently known is the fact that the product present in the package must be directly consumed once the package has been opened or the closure element has been peeled off. The fact is that the package as referred to in the introduction cannot be considered to be a reclosable package.

The object of the invention is to provide a more versatile package as referred to in the introduction, which new package is more multifunctional and which can furthermore be used in various ways by the user.

According to the invention, the package is to that end characterized in that near said lip the two circumferential edges are provided with a closed channel being in communication with said central portion, and wherein at least one of said circumferential edges is provided with a fracture line extending substantially perpendicularly to said channel. An additional use is created with this package according to the invention, viz. metering the product present in the central portion of the package via the channel. The channel functions as a metering opening. The metering channel is opened by tearing off the foil material along the fracture line, and a package is realised which, in addition to the serving function (viz. the peeling off of the closure element from the first shell element) also has a metering function.

In a special embodiment, the package according to the invention is characterized in that at least one of the circumferential edges is provided with at least one notch near the fracture line. The circumferential edge may be provided with a notch on either side of the fracture line, in which case the notch terminates at a position close to the channel. With this embodiment of a package according to the invention, which features a notch near the fracture line and the channel, a simple turning movement will cause the foil material to be locally torn and the channel to be opened, thus creating a package provided with a metering opening.

2

The two different functions render the package according to the invention more versatile in use.

In another embodiment, the closure element is embodied as a flat element lying in the plane of the circumferential edge.

In another embodiment, the closure element is embodied as a second element having an upright circumferential edge and a central portion. Preferably, said first and said second shell element are identical. In yet another advantageous embodiment of the package according to the invention, the closure element and the first shell element are made of the same material. Said parts may also be made of different materials, however.

The invention will now be explained in more detail with reference to the drawing, in which:

FIGS. 1a-1b show a first embodiment of a package according to the present invention; and

FIG. 2 shows another embodiment of a package according to the present invention.

The package 10 that is shown in FIGS. 1a and 1b is made up of a first shell element 11 provided with upright edges 11b, which forms a circumferential edge 11a. The package 10 is furthermore provided with a closure element 12, which is likewise provided with a circumferential edge 12a which, on account of its adhesive property, can be removably yet sealingly placed on the circumferential edge 11a. As a result, the central portion 13 thus formed by the first shell element 11 and the product contained therein can be sealed.

The package according to the invention is in particular suitable for containing a certain amount of a foodstuff, such as milk or yoghurt products, but also liquids or suspension-like foodstuffs such as mayonnaise, ketchup, jam, peanut butter, etc etc. However, the package according to the invention is also suitable for containing a certain amount of a body care product, such as soap, shampoo, hair conditioner, cosmetics, etc etc.

The closure element 12 is provided, in a manner which is known per se, with a projecting lip 14a near the circumferential edge 12a, which a user can pull up with his hand in a known manner, so that the closure element 12 can be peeled off the circumferential edge 11a of the upright edge 11b of the first shell element 11 by its circumferential edge 12a. In this known manner the package 10 is opened in its entirety and the amount of product contained in the central portion 13 becomes available for being used or consumed by the user.

One problem of this currently known package, which may be embodied as a cup for coffee cream, is the fact that the amount of product contained in the package 10 must be consumed directly and cannot be stored for a prolonged period of time once the package 10 has been opened. Consequently, there is a need for a package which on the one hand provides a possibility of opening the package completely, as is the case with the package that is presently known, but which on the other hand also provides a possibility of storing the products contained in the package 10 for some time once the package 10 has been opened, without the risk of spillage or rapid decay.

The embodiment of the package 10 that is disclosed in FIGS. 1a and 1b is to that end characterized in that the package 10 is provided with a channel 15 near the circumferential edge 11a-12b, which channel 15 is formed by the two lips 14a and 14b of the closure element 12 and the first shell element 11, respectively, which are arranged one on top of the other. The channel 15 that is thus formed by the lips 14a-14b arranged one on top of the other is fully enclosed by the material of the lips 14a-14b and opens into the central portion 13 in which the liquid or suspension-like product is contained near the position that is indicated by numeral 15a in the Figure. Furthermore, the lip 14a, and more in particular also

the lip 14b of the first shell element 11 is provided with a fracture line 16, which fracture line 16 extends perpendicularly to the channel 15. The fracture line 16 may be formed by making a small cut in the material of the lip 14a.

Thus it is possible for the user on the one hand to pull the lip 14a up and peel the closure element 12 off the circumferential edge 11a of the first shell element 11, but in addition it is possible to bend the lip 14a (and possibly the lip 14b) back a few times along the fracture line 16, until the lip 14a (and 14b) breaks off due to material fatigue, so that the channel 15 is opened and an outflow opening is thus formed.

The user can thus meter the product contained in the central portion (a foodstuff or a cosmetic product) via the outflow opening formed by the channel (which is open now) by pressing on the first shell element 11 and the closure element 12.

The present package 10 is in particular very suitable for packaging mayonnaise or ketchup products, for example, and the package is opened by peeling off the closure element 12, thus forming a fully open package 10, or a closed package 10 having a small metering opening 15 is formed by breaking off the lip 14a (and possibly the lip 14b).

In FIG. 2 another embodiment of the present invention is shown, in which like parts are indicated by identical numerals.

As in FIG. 1, both the first shell element and the closure element 12 are provided with overlapping lips 14a-14b, which form a channel 15, which channel opens into the central portion 13 of the package 10 at the position indicated at 15a. Both the lip 14a of the closure element 12 and the lip 14b of the first shell element 11 are provided with a fracture line 16 extending perpendicularly to the channel in this embodiment. Furthermore, the two lips 14a-14b are each provided with a notch 17a and 17b, respectively, which notches terminate close to the channel 15.

The user can now turn or break off the lips 14a-14b along the fracture line 16 by turning or twisting the two lips 14a-14b about the elongate axis 18 formed by the channel 15, thus creating an open aperture 15 that functions as a metering opening.

This embodiment, too, provides a multifunctional package 10 according to the invention, which, in addition to the known possibility of being opened by peeling off the shell element 12, also provides a metering function.

In one possible embodiment, the closure element 12 may be embodied as a flat element lying in the plane of the circumferential edge 12a, whilst in another embodiment the closure element 12 may be embodied as a second shell element having an upright circumferential edge 12a as well as a central portion 19 as shown in FIG. 2b. Said first and said second shell element 11 and 12 may be identical. Although it is possible to use different materials for the first shell element 11 and the closure element 12, the two elements are preferably made of the same material. This results in a strong as well as uniform package 10, which in addition provides a certain degree of rigidity when used for metering the product contained in the package 10, the more so because the package 10 can be squeezed empty by the user when metering the product.

The invention claimed is:

1. A package suitable for containing a perishable product, comprising:

a first shell element provided with a generally planar bottom surface and an circumferential wall extending upwardly from the generally planar bottom surface, defining a central cavity, wherein at least a portion of the wall also includes a lower lip;

a closure element placed on the circumferential wall of the first shell element in an adhering manner so as to close the central cavity, wherein at least a portion of the closure element includes a protruding lip, which does not adhere to the lower lip of the circumferential wall of the first shell element, so that the portion of the closure element facilitates peeling the closure element from the first shell element to expose the central cavity; and wherein the first shell element and the closure element also define a closed channel in communication with the central cavity, and wherein the first shell element includes a fracture line extending transversely of the closed channel to facilitate opening the closed channel as a metering opening and notches on either side of the fracture line.

2. A package according to claim 1, wherein the first shell element and the closure element are fashioned from different materials.

3. A package according to claim 1, wherein the first shell element and the closure element are fashioned from the same material.

4. A package according to claim 1, wherein each notch terminates at a point close to the channel.

5. A package according to claim 1, wherein the first shell element and the closure element are substantially identical.

6. A package according to claim 1, wherein the cavity contains a liquid.

7. A package according to claim 1, wherein the cavity contains a suspension-like foodstuff.

8. A package according to claim 1, wherein the cavity contains a gel-like substance.

9. A package according to claim 1, wherein the cavity contains a sweet product.

10. A package according to claim 1, wherein the cavity contains a body care product.

11. A package according to claim 1, wherein the cavity contains ketchup.

12. A package according to claim 1, wherein the cavity contains mayonnaise.

13. A package suitable for containing a perishable product, comprising:

a first shell element provided with a generally planar bottom surface and an upright circumferential wall that projects upwardly from the generally planar bottom surface so as to define a planar circumferential surface that is spaced away from said planar bottom surface, and a central portion for accommodating said perishable product;

a closure element provided with a circumferential edge, which closure element is placed with its circumferential edge on the upright circumferential wall of said first shell element in an adhering relationship with said circumferential surface and in a closing relationship with said first shell;

wherein at least a portion of said closure element is provided at its circumferential edge with a protruding lip, which lip does not adhere to the circumferential edge of said first shell element, for the purpose of substantially completely peeling off said closure element from said first element to expose the central portion, such that near said lip the two circumferential edges are provided with a closed channel arranged in communication with said central portion and further wherein at least one of said circumferential edges is provided with a fracture line extending substantially perpendicularly to said channel.
